(Cl. 290—7)

The invention relates to systems and means for controlling internal combustion engines and other power developing or power utilizing units in various ways and to secure various effects by combined mechanical and electric responsive means.

The invention embraces simple and highly improved mechanical and electrical responsive means for automatically starting as well as stopping or rendering inoperative internal combustion engines or power developing units under certain predetermined conditions.

The invention comprehends a device, adapted to be driven by an internal combustion engine, provided with means which vary in proportion with the speed of said engine for controlling the starting and automatically stopping the same.

One of the objects of the present invention resides in the utilization of speed responsive means for controlling the engine running operation and automatically stop the engine, giving a warning signal when abnormal running conditions have taken place.

Another object of the invention is the provision of means for automatically starting an engine utilizing speed responsive means for rendering the starting means ineffective when the engine has been automatically stopped.

Another object of the invention is the provision of means for disconnecting the starting motor from a current supply when the engine has been automatically stopped and concurrently indicate that the engine has failed and that the starting motor has been disconnected.

Another object of the invention resides in the use of a speed responsive device for automatically controlling the engine and the association of said device with electrical instrumentalities for automatically controlling the normal operation of the engine.

Another object of the invention is the provision of combined electro-mechanical means for automatically shutting down the engine and cutting off the source of electrical energy for the starting means or to the fuel supply when an abnormal condition during the operation of the engine has taken place.

A further object of the invention is the provision of means to automatically close a circuit for producing an alarm or emergency signal as well as initiating the starting of a stand-by engine in case of engine failure.

Another object of the invention resides in the provision of an engine starting system having an emergency signal or alarm which remains opera-

tive until the same is shut off or disconnected from the source of current by an attendant, at which time the automatic control of the starting system is re-established for further operation.

5 Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which

10 15 Figure 1 illustrates semi-diagrammatically a system of control showing in medial vertical section the periodic current producing and speed responsive device;

20 25 Figure 2 is a top plan view of the device shown in Figure 1 with certain parts removed for the purpose of showing the periodic current producing means;

Figure 3 is a top plan view of the speed responsive means forming a part of the device shown in Figure 1;

25 30 Figure 4 illustrates semi-diagrammatically a modified form of the system of control showing in medial vertical section a modified form of the periodic current producing and speed responsive device.

35 40 For purposes of illustrating a practical application of the principles of the invention, the same are embodied in a control system for an internal combustion engine using direct electric current for the starting and ignition means, but it is to be understood that I contemplate the use of the invention to control power developing units provided with different types of instrumentalities to start and operate said units such as pneumatic or fluid pressure which is sometimes employed for starting Diesel and multi-fuel engines.

45 50 Referring to the embodiment illustrated in Figure 1, the control system of the invention includes a suitable source of electrical energy preferably of direct current such as the storage battery 10 having one of its terminals 12 connected by means of lead 13 to ground or a common return means 14 which may be the engine frame, not shown. The other or live terminal 15 of the battery 10 is connected by means of lead 16 to a circuit controlling means or main switch blade 18 manually operable. The manual control could be the ignition switch that normally controls the engine, or may be located in a position 55 to afford remote control means. In case that

the manual circuit control 18 is in a remote position from the engine a safety switch 17 is provided in close proximity to the engine to render the remote control dependent of position of switch 17. The master switch blade 18 is adapted to be moved into engagement with a stationary contact 19 in turn connected by the main conductor 20 through safety switch 17 and lead 21 to the movable armature 23 of the main relay 25. The movable armature 23 carries a contact point 27 adapted to engage the stationary contact 28, supported by the relay 25. The contact 28 is connected by means of conductor 29 to one terminal of the primary winding 31 of the transformer 32. The other terminal of the primary winding 31 is connected by lead 34 to a terminal post 36 insulatingly carried by the casing of a pulsating current producing medium operating from and in unison with the internal combustion engine.

In the preferred form of the invention the pulsating current producing medium or periodic current interrupting and speed governor as particularly shown in Figures 1 to 3 comprises a metallic cup-like or hollow housing 41 having a central depending portion 42 provided with a central bore 43 which affords an elongated bearing surface for the drive shaft 45. The housing 41 is preferably supported by the downwardly extending portion 42 which is adapted to be carried by part of the engine frame (not shown). The drive shaft 45 is provided at its lower end portion 46 with a suitable driving means such as a gear 47 for establishing a driving connection with a driving shaft of the engine with which the device may be used.

Fixedly carried by the drive shaft 45 within the enlarged hollow section 41 of the housing is a cam member 50 formed with a plurality of lobes 52. The lobes 52 upon rotation of shaft 45 are adapted to periodically engage a rubbing block 53 fixedly secured to a pivoted breaker lever or arm 54. The breaker lever or interrupter 54 is pivoted for oscillation around a pintle 56 being insulated therefrom by means of an insulating bushing 57 and in turn electrically connected to the binding post 36 by means of resilient strips 58 and 59. The strip 58 is preferably made of a good current conducting material as for example, copper. The other strip 59 is preferably constructed of a highly flexible material as for example, steel, the latter being used for the purpose of urging the breaker lever 54 toward the cam member 50.

The breaker arm 54 carries at its free end a suitable contact 60 which is adapted to engage a stationary grounded contact 61 adjustably carried by the L-shaped bracket 62 fixedly secured by means of screws 63 to the uniplanar inner surface 64 of the enlarged section 41 of the housing. A condenser 66 is connected across such contacts 60 and 61 to prevent undue arcing by grounding one terminal to the housing and connecting the other condenser terminal by a lead 67 to the binding post 36.

Removably carried by the end of drive shaft 45 above the cam member 50 is the improved speed responsive mechanism of the invention which in response to a predetermined speed operates to move the grounded contacting element 68 into engagement with the relatively stationary contact 69 insulatingly mounted and adjustably carried by the removable cap 70 which closes the cup-like section of the housing 41.

The speed responsive mechanism of the invention comprises a cylindrical frame 72 provided

at its bottom portion with a central opening 73 adapted to receive the end of the drive shaft 45 to which the frame 72 is removably secured by means of a set screw 74 or other suitable means.

5 The top section of the frame 72 is provided with a central transverse recess or slot 75 adapted to receive and guide a pair of rectangularly shaped weights 77 and 78 each being mounted on pivot pins 79 and 80 fixedly carried by the walls of the recess 75. The rectangular weights are formed adjacent to its lower portion with recesses 82 and 83 forming ledges 84 and 85, which project between the spaced circular flanges 86 and 87 of the contacting member 68. A pair of 10 springs 88 and 89 secured to the upper portion of the weights inter-connect and urge the same toward central position retaining the contact element 68 out of engagement with the stationary contact 69 due to the engagement of the ledges 84 and 85 with the lowermost flange 87 of the contact member 68. The springs are so positioned and calibrated with respect to the mass of the rotating weights that when the shaft 45 driven by the engine reaches a predetermined speed, the weights are moved to the position illustrated in dotted lines in Figure 1, carrying the contact 68 due to the engagement of ledges 84 and 85 with the flange 86. The weights 77 and 78 are so arranged in slot 75 that when the predetermined speed is reached by the engine moving the same by centrifugal force to the position illustrated in dotted lines, the lower corner of each weight engages the flat wall of the recess 75. This arrangement provides a simplified 15 form of stop means for the movement of the weight which prevents undue pressure from being exerted by the contact member 68 to the adjustably mounted contact 69.

The contact 69 is carried by the end of a 20 threaded member 90 passing through a threaded bushing 91 insulatingly mounted on the upper wall of the cap 70. The bushing is connected by lead 92 to an insulated binding post 94 also carried by the cap 70. The binding post 94 is connected by means of conductor 96 to the energizing coil 97 of the relay 98, the other terminal of the coil 97 is connected by lead 99 to the conductor 20. The contact 100 carried by the armature of the relay 98 is connected through lead 101 to 25 the conductor 20 and is normally in engagement with the stationary contact 102, the latter connected by means of lead 103 to a terminal of the coil 105 of the main circuit controlling relay 25. The relay 98 is also provided with a second 30 armature 106 carrying contact 107 which is connected by means of lead 108 to conductor 96. The contact 107 is adapted to be moved into engagement with a stationary grounded contact 110.

Means are provided to give a warning signal 35 when the engine is automatically stopped due to an abnormal speed condition which are illustrated in the form of a light bulb 114 having one terminal connected to armature 106 by means of a lead 115 and its other terminal by means of lead 116 to the main conductor 20.

It is contemplated that the stationary contact 28 of the main circuit controlling relay 25 be connected with any of the instrumentalities 40 which normally control the operation of an engine or other power developing units. In the embodiment illustrated the contact 28 is adapted to be connected in case of an internal combustion engine utilizing battery ignition to the ignition system 116 or in cases wherein the system of 45 the invention is employed with Diesel engines

or multi-fuel engines, to an electrically operated device 117 for controlling the throttle or fuel governing supply diagrammatically illustrated in the drawings as 118. The relay 25 is also provided with a secondary armature 120 which is utilized for establishing a ground connection to magneto 121 in cases wherein magneto ignition is used. For such purpose the armature 120 is connected by lead 122 to ground and carries a contact 124 adapted to engage a stationary contact 125, the latter connected to the magneto 121 by lead 127.

In the embodiment of the invention illustrated, the engine starting means are electrically actuated but I contemplate the use of the invention to control engine starting means operated by other sources of power. The electrically actuated means shown are in the form of an electric motor 128 having suitable mechanical connections for cranking the engine and capable of being disconnected from the engine when the engine becomes self-actuated. The electric starting motor shown has one of its terminals 129 grounded while the terminal 130 is connected by lead 131 to one of the stationary contacts 132 of the electromagnetic motor switch 133 while the other contact 134 is directly connected by lead 135 to the battery terminal 15. The contacts 132 and 134 are bridged by a conducting bar 136 insulatingly carried by the magnetic core 137, which is surrounded by the energizing winding 138. One terminal of the switch winding 138 is connected by lead 139 to conductor 29, while the other terminal is connected by lead 140 to stationary contact 141 of relay 142.

The stationary contact 141 is adapted to be engaged by contact 143 carried by the armature of the relay and is suitably grounded thereby. The terminals of energizing winding 144 of the relay 142 are connected respectively to the terminals of the secondary winding 145 of the transformer 32 the primary winding of which is included in the circuit which receives the periodic current flow produced by the action of the oscillating or vibrating arm 54.

The operation of the embodiment of the invention illustrated in Figures 1 to 3 hereinbefore described can be summarized as follows:

When it is desired to start the engine it will only be necessary to move the main switch blade 18 into engagement with the stationary contact 19 and also ascertain that the safety switch 17 is in its closed position. When these conditions are present an operative connection from the live terminal 15 of the battery to the grounded winding 105 of the relay 25 has been established causing the energization of this relay winding. The circuit thus established comprises from the battery terminal 15 through lead 16 to main switch blade 18 engaging contact 19, hence by conductor 20 through safety switch 17 to lead 101 connected through armature contact 109 in engagement with stationary contact 102 by means of lead 103 to one terminal of the winding 105 which has its other terminal connected to ground or to the common return to the battery. The energization of the winding 105 of the relay 25 causes the armature 23 to overcome the action of the spring moving the contact 27 into engagement with contact 28 whereby if the internal combustion engine is of the battery ignition type the circuit of the ignition system including the coil 116 is completed and its energization from the battery is established from the main conductor 20 by lead 21 through armature

23, contact 27 in engagement with contact 28. The engagement of contact 27 with the relay contact 28 also establishes a branch circuit for the energization of the winding 138 of the solenoid switch 133. The branch circuit thus established comprises from contact 28 to conductor 29 hence to lead 139 to one terminal winding 138 and from the other terminal by means of lead 140 to stationary contact 141 in engagement with armature contact 142 which is grounded. The energization of the electro-magnetic switch winding 138 closes a direct circuit from the battery to the starting motor 128 for cranking the engine. This direct circuit comprises from the live battery terminal 15 to lead 135 through switch contacts bridged by bar 136 to lead 131 connected to motor terminal 130 through the motor 128 and hence to ground or common return to the battery.

20 The engagement of the main relay contact 27 with the stationary contact 28 caused by the energization of the relay coil 105 not only connects the battery or source of current 10 to the instrumentalities which control the normal operation of the engine such as the ignition system 116 as well as the solenoid switch 133 which operates to establish a direct connection between the battery 10 and the starting motor 128 for cranking the engine but in addition the engagement of the relay contact 27 with contact 28 also establishes a circuit for the flow of current from the battery 10 to the primary winding 31 and to the periodic current interrupting device 54 connected therewith. The circuit thus established comprises from stationary contact 28 to lead 29 connected to one terminal of the primary winding 31, through this winding by lead 34 to post 36, hence by strip 59 to breaker arm 54, contact 60 adapted to engage the stationary grounded contact 61.

25 It should be noted that rotation of the engine will rotate the drive shaft 45 and thereby cause a periodic interruption in the battery current flowing through the primary winding 31 of the transformer 32, due to the fact that the cam lobes 52 periodically engage the rubbing block 53 of the arm 54, separating the contacts 60 and 61.

30 When the engine becomes self-actuated and 50 during the time that the same is in operation the rapidity of the interruption of the current in the primary winding 31 caused by the movement of the breaker arm 54 is such that an alternating current of sufficient value is induced 55 in the secondary winding 145 to cause the energization of the relay winding 144 connected therewith. The energization of the winding 144 will cause the separation of the contact 143 from 60 141 overcoming the action of the relay spring opening the circuit of the switch winding 138. The de-energization of winding 138 will cause the disengagement of bar 136 from the switch contacts 132 and 134 interrupting the flow of current between the battery and starting motor 128 rendering the same ineffective, a condition 65 which will take place during the time the engine is running.

70

It is important to note that the ratio of turns between the primary and secondary windings of the transformer 32 is such that when the engine is running under its own power or at any speed above cranking speed, the alternating current induced in the secondary winding should be of sufficient value to energize the relay winding 144 so as to keep apart the contacts 143

and 141. However, when the periodicity of the interruption of the breaker arm 54 falls below such predetermined value or the engine speed is below cranking speed, which may take place when the engine stalls, the value of the alternating current induced and flowing through the relay winding 144 should be insufficient to overcome the force of the spring so that when such condition takes place, the armature contact 143 will be urged into engagement with the stationary contact 141, thus re-establishing the connection of the electro-magnetic switch energizing winding 138 to move the connecting bar 136 with the switch contacts 132 and 134 to cause the energization of the starting motor from the battery for cranking the engine.

In the event that the engine operates above certain predetermined speed, such abnormal speed will be transmitted by means of gear 47 to the drive shaft 45, the latter rotating the weights 71 and 78 so that the same will move to the position indicated in dotted lines, wherein due to the engagement of the ledges 84 and 85 with the upper flange 86 of the grounded contact member 68 the same is moved into engagement with the stationary contact 69, thus establishing a circuit from the battery to the energizing winding 97 of relay 98. The circuit thus established includes from the main conductor 20 through lead 99 to winding 97, hence by lead 96, conductor 94 and to stationary contact 69 in engagement with the grounded contact 68 forming the common ground return to the terminal 12 of the battery. The energization of winding 97 overcomes the relay spring separating contact 100 from 102, thereby interrupting the flow of current from the battery to the main relay winding 105. The de-energization of winding 105 permits the relay spring to separate the contact 27 from contact 28, interrupting the flow of current to the instrumentalities which controls the normal running operation of the engine, such as the ignition system as well as to the starting motor magnetic switch 133 and the primary 31 of the transformer 32, so that the engine is stopped and the starting motor is rendered ineffective. Concurrently with the separation of contact 101 from 102, the engagement of contact 107 with contact 110 takes place providing an auxiliary ground connection for the winding 97 as the second armature carrying contact 107 is simultaneously operated. The engagement of contacts 107 and 110 takes place before the time when contact 68 is moved out of engagement with contact 69, caused by the de-acceleration of the engine, so that the energization of the winding 97 is not interrupted. The engagement of contact 107 with 110 also completes the circuit of the lamp bulb 114 giving a visual warning signal because the lamp 114 has one terminal connected by means of lead 116 to the main conductor 20 and the other terminal by means of lead 115 to ground through the engaging contacts 107 and 110.

It should be noted that it will be necessary to open the main circuit switch 18 to interrupt the flow of current to both the relay winding 97 and warning signal 114 and that such action is necessary to re-establish the engagement of the main contacts 101 and 102 of this relay. Moreover that while the contact 141 is in engagement with contact 143 of the relay 142 no current flows through the winding 138 of the starting motor magnetic switch 13 due to the fact that the circuit between the contact

28 and battery terminal 15 has been interrupted by the movement of the armature 23 to separate contact 27 from contact 28, so that the starting motor 128 remains ineffective to crank the engine until the winding 97 is de-energized.

In the modified form of the invention shown in Figure 4 there is illustrated a control system for an internal combustion engine which secures the results accomplished by the form of the invention hereinbefore described. The system illustrated in Figure 4 differs from the one hereinbefore described in that the main and auxiliary relays which control the connections from the battery to the instrumentalities which control the normal operation of the engine are dispensed with and the function performed by these relays is produced by means actuated by a modified form of the speed responsive means of the invention. In the modified form of the control system, the live battery terminal 15' through wire 16', main control switch blade 18', safety switch 17' and main conductor 20' is connected to a terminal post 150 carried by a switch housing 151 of insulating material mounted upon the top section of the cap 70' which encloses the cup-like housing 41' of the pulsating current producing device.

The post 150 pivotally supports within the housing 151 the central portion of a switch blade or current conducting arm 152. The arm 152 is provided at each end with contacts 153 and 154, the latter normally urged into engagement by means of spring 157 with a contact 155 carried by the binding post 156 supported on the horizontally disposed wall of the switch housing 151. The lower surface of the arm 152 adjacent to contact 153 is adapted to be engaged by the end of a post or switch actuating member 158. The post 158 projects within the cap 70' by passing through an opening 159 and has its lower extremity in contact with a switch actuating bar 160. The bar 160 is pivotally supported at one end by the stationary bracket 161 fixed to the top inner surface of the cap 70' and is provided adjacent to its pivotal point with an integrally formed depending finger 162 which projects into an opening 163 provided on a flat plate 164 secured to one end of a tensioning blade or resilient member 165 for urging the free end of the switch actuating bar 160 into engagement with a projection or stop 166 carried by the lateral wall of the cap 70'. The tensioning blade 165 has its other end fixed to the lateral wall of the cap 70' as at 168 by means of the screw 169. Coacting with the tensioning blade 165 is the end 170 of the adjusting member or screw 171 which is threaded to the lateral wall of cap 70' and is adapted to be locked in position by means of the nut or threaded member 173. The bar 160 is provided at its central portion with a steel plate or a hard wearing disk 175 adapted to be engaged by a stud 176 preferably made of a molded plastic material which is carried at the end of the member 68'. The member 68' is of similar configuration to the one hereinbefore described and is actuated by a speed responsive mechanism incorporating the same structural features and functioning in similar manner as the one hereinbefore described.

In the modified form of the invention the pulsating current producing mechanism is similar to the one shown and described in connection with the preferred form of the invention, therefore the same is diagrammatically illustrated in Figure 4 and comprises fundamentally a pivoted breaker arm 54' insulatingly supported within the

housing 41' and being connected to the terminal post 36'. The arm 54' is provided with a rubbing block 53' and a contact 60' urged by a spring 59' into engagement with a grounded contact 61' carried by the housing 41'. Upon rotation of the shaft 45' driven by the engine the contact 60' is periodically separated from the grounded contact 61' by means of cam lobes 52' engaging the rubbing block 53' of breaker arm 54', thereby causing the periodic interruption of the current flowing in the primary winding 31' of the transformer 32'.

The coordination and operation of the modified form of the invention shown in Figure 4 can be summarized as follows:

When it is desired to start the operation of an engine with which this form of the invention is associated, the switch blade 18' of the master switch, which as hereinbefore stated can be located in a position remote from the engine, is moved into engagement with the stationary contact 19' and by also closing the safety switch 17' or ascertaining that the same is in closed position, a circuit is established between the battery and the instrumentalities which control the running operation of the engine. The circuit thus established comprises from the battery terminal 15' through lead 16', main switch blade 18', engaging stationary contact 19' through safety switch 17' by main conductor 20' to terminal post 150 hence by switch arm 152, to the engaging contacts 154 and 155 to the binding post 156 and by means of lead 178 to the instrumentalities which control the normal operation of the internal combustion engine such as the ignition system 116' or if the engine is of the Diesel or multi-fuel type of an electrically operated device 117' which operates to fuel governing means 118'.

The closing of the master switch 18' concurrently establishes a branch circuit for the energization of the winding 138' of the starting motor magnetic switch 133'. The circuit thus established comprises from the conductor 178 to wire 29' hence to lead 139' to one terminal of the winding 138' and from the other terminal of this winding by means of lead 140' to the stationary contact 141' in engagement with the armature contact 143' to ground.

The energization of the electro-magnetic switch winding 138' closes a direct circuit from the battery to the starting motor 128' for cranking the engine. This direct circuit comprises from the live battery terminal 15' by lead 135' to switch contact 134' through bar 136' to switch contact 132' hence by lead 131' to the terminal 130' of motor 128' and through contact 129' to ground or common return to the battery terminal 12'. The motor 128' will crank the engine in the well known manner and the same is provided with mechanical connections which will disengage when the engine becomes self-actuated.

The engagement of the switch blade 18' with the stationary contact 19' under the conditions hereinbefore enumerated with respect to the safety switch 17' will also establish a second branch circuit for the flow of current from the battery to the primary winding 31' and to the periodic current actuating devices 54' connected therewith. The circuit thus established comprises from the conductor 178 to lead 29' connected to one terminal of the primary winding 31' through this winding and by lead 34' to the binding post 36' to the breaker arm 54' carrying contacts 60' adapted to engage the stationary contact 61' connected to ground or common battery return.

When the engine becomes self-actuated the rapidity of the interruption of the current caused by the movement imparted to the breaker arm by the cam lobes is such that an alternating current is induced in the secondary winding 145' of sufficient value to cause the energization of the relay winding 144' directly connected therewith. The energization of the relay winding 144' will separate and retain the contact 143' out of engagement with contact 141' overcoming the action of relay spring, thereby interrupting the flow of current to electro-magnetic switch winding 138' so as to open the direct connection between the battery and the starting motor 128' and thereby stop the same.

If the engine operates above certain predetermined speed, the speed will be transmitted by means of gear 47' to the drive shaft 45', the latter rotating the weights 11' and 18' moving the same to the position indicated in dotted lines in Figure 4. Due to the engagement of the ledges 84' and 85' with the upper flange 86' of the member 68' the same moves the pivoted arm 160 to the position indicated in dotted lines and thereby moving the switch actuating bar 158 to rock the contact arm 152 separating the contact 154 carried thereby from contact 155 as indicated in dotted lines in Figure 4. The disengagement of contact 154 from contact 155 will stop the flow of current from the battery to the conductor 178 and thereby render the instrumentalities which control the normal operation of the engine ineffective as well as the starting motor control circuit so that the engine is stopped and the starting motor becomes ineffective to crank the engine.

It should be noted that when the switch arm 152 is moved to the position indicated in dotted lines in response to the action of centrifugally operated weights, the contact 153 is urged into engagement with a contact 180 carried at the end of the binding post 181, carried by the switch housing 151. The terminal post 181 is connected by means of lead 183 to the lamp bulb 114' which is grounded as at 184, so that a warning signal will be produced when the engine has been stopped and the starting motor rendered ineffective due to an abnormal speed condition. It is also contemplated that in lieu of using a visual warning signal, audible signals may be employed. I have found that an electric horn can be effectively used in lieu of the lamp 114'.

It should be noted that the return of the speed responsive means from the position illustrated in dotted lines to the one indicated in full lines, due to the stopping of the engine, will not affect or change the position of the switch arm 152 and therefore I have provided means for resetting the switch arm from the position illustrated in dotted lines to that in full lines. The means shown are in the form of a slideable bar 185 manually operated which projects outwardly of the casing 151 and has one end in engagement with the switch arm so that by applying pressure the switch arm 152 is moved from the position illustrated in dotted lines to that shown in full lines, re-establishing the circuit between the battery and the instrumentalities which normally control the operation of the engine such as the ignition system 116', as well as the controlling means for the operation of the starting motor 128', including the solenoid switch 133' and the primary winding 31' which receives the pulsating current pro-

duced by the actuation of the breaker arm 54' when the engine drives the shaft 45'.

It should be noted that the arrangement of the component elements for effecting the automatic stopping of the engine upon a predetermined abnormal speed condition is such that the same is capable of performing this operation at different engine speeds. This feature is secured by having the springs coacting with the centrifugally operated weights positioned at a point highly accessible so that it is only necessary to change their tension in order to make the device capable of operating at different speeds.

In the form of the invention shown in Figures 1 to 3, the adjustability of the stationary contact 69 carried by the cap 10 provides additional means for changing the speed at which it is desired to disconnect the engine. The change of position of stationary contact 69 also changes the distance of travel imparted by the centrifugally operated weights to the contact 68 before the same engages the contact 69 to stop the engine so that the speed at which the engine becomes ineffective can be materially changed.

In the embodiment of the invention shown in Figure 4, this additional feature for changing the predetermined speed at which it is desired to stop the engine when an abnormal speed condition takes place is secured by changing the tension of the resilient blade 165 which is accomplished by flexing the same through the screw 171. Any change in the tension of blade 165 is imparted to the switch actuating blade 160 through finger 162, so that a different centrifugal force is required to move the blade 160 from the full to the dotted lines position and therefore without the necessity of modifying the springs or changing their tension the speed at which the engine is rendered ineffective can be materially changed.

The control system of the invention is highly effective in installations where more than one engine is used as the same automatically initiates the operation of a stand-by engine and thereby insures the continuity of operation when the main engine is automatically shut off. This use of the invention may be secured in either of the forms shown by connecting in parallel with the warning signal 114 or 114' the winding of a relay, the armature of which operates to close the master switch such as 18 or 18' of the control system associated with a stand-by engine and thereby render the same operative.

The control system of the invention by the use of means dependent for its operation upon the self-actuation of the engine, as hereinbefore pointed out, also operates as automatic means to crank the engine whenever the same stalls. In this respect it is important to note that the windings of the transformer and relay associated therewith are so designed that the same take advantage of the rapid rise in the voltage of the battery when the engine becomes self-actuated, as the heavy load imposed by the starting motor or battery while cranking the engine is not present at the instant the engine starts or becomes self-actuated, moreover the energization of the starting motor through this control is such that unless the engine stalls, the starting motor will not be connected to the cranking engine, thus preventing the possibility of applying the cranking motor while the engine is rotating.

In the forms of the invention I have illustrated an electric starting motor as engine starting means, however, I contemplate the control sys-

tem of the invention to be utilized for governing the functioning of valves or other apparatus which control the application of power to other types of engine starting means.

5 In the forms of the invention illustrated, I have shown diagrammatically several relays constituting elements of the controlling means of the invention. The relays can be of standard suitable type, however, I prefer to use a relay including a substantially balanced pivoted armature as particularly shown and disclosed in Williams Patent No. 2,021,396, issued November 19, 1935. I have found this type of relay very effective and reliable under all conditions of operation

15 to which the system may be put.

It is apparent that, within the scope of the invention, modifications and different arrangements may be made other than is herein disclosed, and the present disclosure is illustrative 20 merely, the invention comprehending all variations thereof.

What I claim is:

1. The combination with an internal combustion engine having an electrically operated 25 starter; of a battery; a pulsating current producing medium operated from and in unison with the engine; a circuit normally open leading from the battery to the electrically operated starter; a magnetically controlled switch for the circuit 30 of said electrically operated starter; an energizing coil for moving to closed position the magnetically controlled switch to close the electrical 35 operated starter circuit; a transformer; the primary winding of which is included in the circuit which receives the pulsating current; a control circuit relay coil energized from the secondary of the transformer; a second relay operable to control the instrumentality which maintains 40 said engine in normal operation; manually operable means for establishing a flow of current from the battery through a circuit including the armatures of both relays in series with the energizing coil of the magnetically controlled switch; a pair of normally open contact points controlled 45 by and operated in unison with the current pulsating medium for rendering ineffective the manually established circuit under predetermined conditions.

2. The combination with an internal combustion engine having an electric motor-operated 50 starter; of a direct electric current source; a pulsating current producing medium operated from and in unison with the engine; a circuit leading from the current source to the starter 55 motor; a transformer having its primary winding included in the circuit which receives the pulsating current; a relay having its coil energized from the secondary of the transformer for controlling the starter motor circuit; a second relay operable to disconnect the instrumentality which 60 maintains said engine in normal operation after the same has been started; a pair of normally open contact points controlled by and operated in unison with the current pulsating medium 65 for establishing a flow of current to the second relay coil and render the same operative to disconnect said engine instrumentality to stop the engine.

3. The combination with an internal combustion engine having an electric motor-operated 70 starter; a battery; a pulsating current producing medium operated from and in unison with the engine; a circuit normally open leading from the battery to the electric motor; a magnetically controlled switch for closing the electric motor

circuit; an energizing coil for moving to closed position the magnetically controlled switch; a transformer, the primary winding of which is included in the circuit which receives the pulsating current; a relay coil energized from the secondary of the transformer; a second relay operable to control the instrumentality which maintains said engine in normal operation; means for connecting the armatures of both relays with the energizing coil of the magnetically controlled switch to the battery; a pair of normally open contact points controlled by and operated in unison with the current pulsating medium for controlling the flow of current to the second relay coil whereby when the engine exceeds a predetermined speed the current to the second relay is interrupted thereby rendering said instrumentality ineffective.

4. The combination with an engine and electrically controlled means for the same, of engine starting means; a control circuit for said starting means; a stationary contact; a movable contact normally urged into engagement with said stationary contact; means driven by the engine actuating on said movable contact to cause the periodic separation of said contacts to set up an intermittent current in said control circuit, the value of which varies in proportion to the speed of the engine for rendering ineffective the starting means when the engine becomes self-actuated; an electrically actuated instrumentality operable to maintain the engine in operation; a circuit for rendering said instrumentality effective; a second movable contact; a relatively stationary contact adapted to be engaged by said second movable contact, both of said contacts included in the circuit which renders the engine instrumentality effective; a mechanism actuated by said engine driven means connected to said second movable contact to cause the engagement of said second movable contact with the relatively stationary contact when the engine reaches a predetermined abnormal speed whereby the said engine instrumentality is rendered ineffective and the engine is stopped.

5. In combination, electro-responsive means and circuits therefor; manual switching means for connecting said electro-responsive means to a current source whereby an operative connection is established, causing the operation of an engine starting means; means responsive to the self actuation of the engine for disconnecting said electro-responsive means from the current source rendering said operative connection ineffective during the time the engine is self-actuated and adapted to re-establish said connection when the engine stalls; and speed-responsive means operable to disconnect said electro-responsive means from the current source after the engine has been in operation upon an abnormal speed engine operating condition whereby said operative connection becomes ineffective.

6. The combination with an engine and an electrically controlled starter for the same, of an electric circuit including the primary winding of a transformer, a periodic circuit interrupter driven by said engine functioning to set up an intermittent current in said circuit as long as the engine is in normal operation; speed responsive means actuated concurrently with said interrupter for effecting under predetermined speed the interruption of the flow of intermittent current in said circuit; a second circuit in which is included the secondary winding of said transformer; and electrical connections between

the second circuit and the starter through which the supply of current to the starter is controlled.

7. In combination, a current source; an engine starting motor having conducting means for the flow of current thereto from a current source; an electro-magnet for establishing when energized in operative connection for the energization of said starting motor from said current source; means associated with said electro-magnet dependent upon the speed of the engine for rendering said operative connection ineffective; and means associated with said electro-magnet responsive to an abnormal engine speed for rendering said operative connection ineffective and maintaining the same in such condition.

8. In combination an internal combustion engine; a current supply; an electrically operable control device for controlling the operation of said internal combustion engine; a controller; an electro-magnet; a switch operated to closed position by said electro-magnet for connecting through said controller the control device to the electric supply; means for controlling the energization of said electro-magnet including a speed responsive device operable upon predetermined engine speed for rendering the energization of said electro-magnet ineffective whereby the electrically operated control device is disconnected from the electric supply to stop the engine.

9. In combination, an internal combustion engine; an electric current supply; electrical apparatus connected with said internal combustion engine and electric supply for starting the engine; an internal combustion engine control device; plural control circuits for said device; a manual controller for rendering said control circuits operative; an electro-magnetically operated switch for connecting said internal combustion engine control device to the electric supply, said switch including a control circuit closing coil energized by the electric current supply; a circuit for said coil including closed contacts actuated by a relay coil; and means responsive to a predetermined speed of the internal combustion engine for connecting the relay coil to the electric supply for opening the closed contacts whereby the internal combustion engine control device is disconnected from the electric supply to render the engine ineffective.

10. The combination with an engine and electrically controlled means for starting and stopping the same, of electric circuits controlling the operation of the engine starting means and of instrumentalities which maintain the engine in running operation; a stationary contact; a movable contact normally urged into engagement with said stationary contact; means driven by the engine to cause the periodic separation of said contacts to set up an intermittent current, the value of which varies in proportion to the speed of the engine for controlling the starting means when the engine becomes self-actuated; an auxiliary movable contact; a relatively stationary contact adapted to be engaged by said auxiliary movable contact, both of said contacts included in the circuit which controls the operation of the engine instrumentalities; and speed responsive means actuated by said engine driven means and being connected to said auxiliary contact to cause its engagement with the stationary contact when the engine reaches a predetermined abnormal speed whereby the said engine instrumentalities are rendered ineffective and the engine is stopped.

11. In combination, an electro-magnet; switching means for connecting said electro-magnet to a source of current whereby a flow of current is established causing the energization of an engine starting means from a source of current; speed responsive means associated with said electro-magnet operable when the engine reaches a predetermined speed for rendering said starting means ineffective; auxiliary means associated with speed responsive means and said electro-magnet for interrupting the operation of the engine when a predetermined speed is exceeded rendering the starting means ineffective; and means controlled by said auxiliary means to energize means adapted to indicate that the normal operation of the engine has been interrupted and the starting means are ineffective.

12. In combination, a source of power; engine starting means; normally open connections for establishing a flow of power to said engine starting means from said source; means to automatically close said connections; auxiliary means associated with said connections rendered operable by the operation of the engine for interrupting the flow of power to said starting means when the engine has been started; and speed responsive means driven by said engine for shutting off the engine and concurrently rendering said automatic connection closing means ineffective upon the presence of an abnormal engine speed.

13. In combination, a source of power; starting means for an engine; normally open connections for establishing a flow of power to said engine starting means from said source; means to automatically close said connections; auxiliary means actuated by the engine associated with said connections and said source for rendering the flow of power ineffective to said starting means upon self-actuation of the engine; and speed responsive means concurrently actuated with said auxiliary means operable to stop the engine giving a warning signal when the engine reaches a predetermined speed.

14. In combination, a source of power; engine starting means; normally open connections for establishing a flow of power to said engine starting means from said source; electro-responsive means operable to close said connections; auxiliary means dependent for functioning upon the running of the engine associated with electro-responsive means for opening the connection established by the electro-responsive means between the starting means and the source; and speed responsive means concurrently actuated with said auxiliary means operable to stop the engine and maintaining said electro-responsive means ineffective when the engine reaches a predetermined speed.

15. In combination, a source of power; engine starting means; normally open connections for establishing a flow of power to said engine starting means from said source; electro-responsive device operable to close said connections; auxiliary means dependent for functioning upon the running of the engine associated with said electro-responsive device for rendering the flow of power ineffective to the starting means upon self-actuation of the engine; a second electro-responsive device operable to control an instrumentality which maintains said engine in operation; and speed responsive means driven by said engine associated with both of said electro-responsive devices for rendering said instrumentality ineffective and opening the connections to the en-

gine starting means when the engine reaches a predetermined speed.

16. The combination with an internal combustion engine provided with starting means; a power source; a pulsating current producing medium operated from and in unison with the engine; connections normally open leading from the source of power to the starting means; means for closing said connections; a transformer, the primary winding of which receives the pulsating current; an electro-responsive device connected to the secondary of the transformer to control said connection closing means; a second electro-responsive device operable to control an instrumentality which maintains said engine in running operation; a movable contact member; a relatively stationary contact; and means controlled by and operated in unison with the current pulsating medium for moving said contact into engagement with said stationary contact when the engine exceeds a predetermined speed whereby the current flow to the second electro-responsive device is interrupted for rendering said engine instrumentality ineffective.

17. The combination with an internal combustion engine having an electrically-operated starter; a current supply; a pulsating current producing medium operated from and in unison with the engine; a circuit normally open leading from the current supply to the starter; a switch for closing the circuit to said starter; an energizing coil for moving to closed position said switch; a transformer, the primary winding of which is included in the circuit which receives the pulsating current; a relay energized from the secondary of the transformer; a second relay operable to control an instrumentality which maintains said engine in running operation; means for connecting in series the armatures of both relays with the energizing coil of said switch to the current supply; a movable contact member; a relatively stationary contact and means controlled by and operated in unison with the current pulsating medium for moving said contact into engagement with said stationary contact when the engine exceeds a predetermined speed whereby the current flow to the second relay is interrupted for rendering said engine instrumentality ineffective.

18. The combination with an engine having electrically operated starting means; of a current source; a pulsating current producing medium operated from and in unison with the engine; speed responsive means mechanically associated with said medium; switching means controlled by said speed responsive means; a circuit normally open from the starting means to the current source; a solenoid switch operable to close circuit of the starting means; a transformer; the primary winding of which is included in the circuit which receives the pulsating current; a relay operable to open the circuit of the solenoid switch when the engine becomes self-actuated by having its coil energized from the secondary of the transformer; an electrically operable instrumentality for maintaining said engine in normal operation; means for establishing an effective connection for the flow of current to the energizing coil of the solenoid switch and concurrently to said electrically operable instrumentality through the switching means controlled by the speed responsive means whereby when the engine exceeds a predetermined speed flow of current to the solenoid switch and the electrically operable instrumentality is interrupted.

19. The combination with an engine having

electrically operated starting means; of a current source; means for energizing said starting means from said source to start said engine; a pulsating current producing medium operated from and in unison with the engine for rendering said starting means ineffective when the engine becomes self-actuated; mechanical means associated with said current producing medium; switching means controlled by said mechanical means; an electrically operable instrumentality for maintaining said engine in normal operation; means for establishing an effective connection for the flow of current from said source to the electrically operable instrumentality through the switching means controlled by the mechanical means whereby when the engine exceeds a predetermined speed the said effective connection is rendered ineffective.

20. In combination, electro responsive switching means; normally open connections between 20

said means and a current source; engine starting means rendered operable by the energization of said electro responsive switching means; an electrically operable instrumentality for maintaining the engine in operation; normally open connections between said instrumentality and a current source; manual switching means for closing said connections energizing said electro responsive means and rendering operable said instrumentality; a mechanism driven by the engine; means actuated by said mechanism for rendering the energization of the electro responsive switching means ineffective during the time the engine is self-actuated; and speed responsive means operated by said mechanism and in unison with the means actuated thereby for rendering the operation of said instrumentality ineffective when said mechanism exceeds a predetermined speed whereby the engine is stopped.

WILLIAM J. WILLIAMS.
